ARC REGULATOR

Harry H. Strong, Toledo, Ohio

Application March 9, 1934, Serial No. 714,818

12 Claims. (Cl. 171—312)

This invention relates to arc regulators, particularly adapted for effecting and regulating the feed of the electrodes of the arc of a motion picture projector, and the principal object of my invention is to provide a new and improved arc regulator of this character.

In the drawing accompanying this specification, and forming part of this application, I have shown, for purposes of illustration, one form 10 which my invention may assume, and in this drawing:

Figure 1 is a view illustrating the motor employed to feed the electrodes, and showing also the connections of the motor into the circuit, 15 while

Figure 2 is a diagrammatic view showing the electrical arrangement of all of the parts.

Figure 3 is a diagrammatic view showing a conventional way in which the motor may be 20 mechanically connected to the electrodes.

The embodiment of the invention herein disclosed comprises an arc 12 having electrodes 10 and 11 advanced and retracted through any suitable mechanism (not shown) by means of an electric motor 13 provided with a frame 14 rotatably supporting an armature 15 provided with a commutator 16 contacted by brushes 17 and 18 respectively carried by brush holders 19 and 20 supported by the motor frame 14, as shown. 25

The motor frame 14 also supports a pair of field poles 21 and 22, the pole 21 having a first field coil 23 arranged to set up a magnetic flux in one direction, and the pole 22 having an opposing field coil 24, arranged to set up a magnetic flux 30 in the reverse direction.

The embodiment of my invention herein shown is designed for use with either direct or alternating current, and includes three parallel circuits 35 between the line wires 30 and 31. A first circuit, herein designated as the armature circuit, consists of a connecting conductor 40, the brush 17, the armature 15, the brush 18, and a connecting conductor 41. A second circuit, herein designated as the potential circuit, consists of a connecting conductor 36, the potential field coil 23, a connecting conductor 37, a variable resistor 39, and a connecting conductor 42. The third circuit, herein identified as the current circuit, consists of a connecting conductor 32, the current field coil 24, a connecting conductor 34, the arc 12, and a connecting conductor 35.

With these connections it will be obvious that the current field coil 24 is connected in series 55 with the arc 12, so that the current field will be proportional to the current flowing through the arc 12, and that the potential field coil 23 is connected across the arc 12, so that the potential field will be proportional to the voltage drop across the arc 12. It is well known, of course, that 60 as the electrodes 10 and 11 separate, the voltage

drop across the arc 12 increases, and the current decreases, and that the reverse occurs when the electrodes 10 and 11 approach each other, and accordingly it will readily be understood that with the proper adjustment in strength between 5 the potential field coil 23 and the current field coil 24, the decrease in current and increase in voltage drop, as the electrodes 10 and 11 separate, will cause the potential field coil 23 to predominate over the current field coil 24, and the resultant 10 field to be in one direction, while the increase in current, and the decrease in voltage drop, as the electrodes 10 and 11 approach each other, will cause the current field coil 24 to predominate over the potential field coil 23, and the resultant 15 field to be in the reverse direction.

Inasmuch as the armature is always energized in the same way, the change in direction of the resultant field will obviously change the direction of rotation of the armature 15, and accordingly, with the proper connections between the motor and the electrode feeding mechanism, the predominance of the potential field coil 23, when the electrodes separate too far, will cause the armature 15 to rotate to advance the electrodes 25 10 and 11, and the predominance of the current field coil 24, as the electrodes approach too closely, will cause the armature 15 to rotate in the reverse direction, to separate the electrodes.

Under normal motor conditions, however, the 30 speed of rotation of the motor armature varies inversely as the strength of the field, and accordingly, with normal motor conditions, the armature 15 would rotate with increasing speed as the electrodes approach the proper spacing 35 and the resultant field approaches zero, and then would tend to rotate at maximum speed in the reverse direction, as soon as the resultant field had changed polarity. In order to eliminate this undesirable action I form the circuit of the armature 15 of such high resistance that the impedance drop is substantially equal to the entire line voltage, and the counter-electro-motive-force drop across the armature 15 is negligible, at substantially all speeds at which the armature 40 rotates, so that the current flowing through the armature circuit is substantially unaffected by change in counter-electro-motive-force, and remains substantially constant, at all times. Under these conditions the tendency of the armature 45 50 to speed up in response to resultant field weakening is substantially eliminated, and further, because of the constant current in the armature 15, the armature 15 actually operates faster upon increase in resultant field strength, because of 55 the increase in torque resulting from the fact that with the current substantially constant in the armature 15, the torque is directly proportional to the field strength.

I accordingly produce a condition wherein the

motor speed decreases with decrease in field strength through a zero speed at the point of zero field strength, and then increases in speed in the reverse direction as the resultant field increases in strength also in the reverse direction.

Obviously, with the parts properly proportioned, the potential field and the current field will exactly balance at that point at which the electrodes are properly spaced to secure the desired arc, and the armature 15 will maintain the electrodes so spaced. However, variation in operating conditions may unbalance the two fields, and in order to compensate for this action I form 15 the resistor 39 variable, to provide for adjustment.

I have found that placing the potential field coil 23 and the current field coil 24 on the separate pole pieces 21 and 22, on opposite sides 20 of the armature 15, provides a motor that operates satisfactorily on either direct or alternating current.

In some instances it may be desirable to include in the motor dead poles 43 intermediate the 25 active poles 21 and 22.

Under these circumstances I attribute the successful operation on alternating current to the provision of a construction reducing mutual induction between the potential field coil 23 and 30 the current field coil 24.

It seems that inductive reactance between the two fields tends to delay change in predominance of the fields, and that the placing of the two coils on the separate poles reduces this reactance below the amount effective to cause objectionable delay. It seems that not more than approximately three-fourths of the flux of either field should react inductively with the winding of the other field.

40 However, my invention is not to be taken as limited by or to any theory or explanation, nor to any particular means or use; on the contrary, while it will be obvious to those skilled in the art that the embodiment of the invention herein disclosed accomplishes the principal object of the invention, it also will be obvious that my invention is adapted for uses and purposes not herein particularly referred to, and that the embodiment thereof may be variously changed and 45 modified, without departing from the spirit of my invention, and accordingly, it will be understood that the embodiment herein disclosed is 50 illustrative only, and that my invention is not limited thereto.

55 I claim:

1. An electric motor, including: an armature; a single stator-core for coacting with said armature; a winding for said stator-core, said winding when energized tending to produce a flux in said stator-core effective to turn said armature in one direction; another winding for said stator-core, said winding when energized tending to produce a flux in said stator-core effective to turn said armature in the opposite direction while said first named winding is energized; said armature responding to the resultant flux in said stator-core; said windings being disposed on said stator-core in spaced relation so as to promote leakage of flux between said windings.

70 2. An electric motor, including: an armature; a single stator-core for coacting with said armature; a winding for said stator-core, said winding when energized tending to produce a flux in said stator-core effective to turn said armature in one direction; another winding for said

5 stator-core, said winding when energized tending to produce a flux in said stator-core effective to turn said armature in the opposite direction while said first named winding is energized; said armature responding to the resultant flux in said 10 stator-core; said windings being disposed on said stator-core in spaced relation, the relation between said windings and core being such that the flux leakage between said windings is approximately one-fourth of the flux of the respective 15 windings.

3. An electric motor, including: a single stator-core having a pair of poles; an armature coacting with said poles; a differential field winding for said poles, said winding comprising two 20 components, one of said components being disposed preponderately on one pole of said pair of poles and the other of said components being disposed preponderately on the other pole of said pair of poles; and connection means for said 25 winding whereby said components may be simultaneously energized and whereby one of said components is adapted to coact with said armature in a sense opposite from said other component.

4. An electric motor, including: a single stator-core having a pair of poles; a differential field winding for said poles, said winding comprising two components, one of said components being disposed preponderately on one pole of 30 said pair of poles and the other of said components being disposed preponderately on the other pole of said pair of poles; a pair of windingless interpoles alternated with the poles carrying said components; an armature coacting with said poles and interpoles; and connection means for said winding whereby said components may be simultaneously energized and whereby one of said components is adapted to coact with said armature in a sense opposite from said other component. 40

5. An electric motor, including: an armature; a single stator-core for coacting with said armature; a winding for said stator-core, said winding when energized tending to produce a flux in said stator-core effective to turn said armature in one direction; another winding for said stator-core, said winding when energized tending to produce a flux in said stator-core effective to turn said armature in the opposite direction; means for energizing said windings simultaneously whereby said armature turns in a direction dependent upon the predominance of one of said windings over the other; said windings being disposed on said stator-core in spaced relation so 50 that relative changes in the energizations of said windings causes substantially contemporaneous changes, in said predominance, substantially proportionate to said relative changes in energizations. 55

6. An alternating current electric motor, including: an armature; a single stator-core for coacting with said armature; a winding for said stator-core, said winding when energized tending to produce an alternating flux in said stator-core 65 effective to turn said armature in one direction; another winding for said stator-core, said winding when energized tending to produce an alternating flux in said stator-core effective to turn said armature in the opposite direction; means for energizing said windings simultaneously whereby said armature turns in a direction dependent upon the predominance of one of said windings over the other; said windings being disposed on said stator-core in spaced relation so 70 75

that relative changes in the energizations of said windings causes changes in said predominance substantially proportionate to said relative changes in energizations.

5. 7. In combination: an electrical device having a movable element the position of which influences the current through said device and the potential drop around said device; means for maintaining constant the relation between the 10 current through said device and the potential drop around said device, comprising, an electric motor drivingly connected to said movable element, said motor having an armature and a single stator-core for coacting with said armature; a winding for said stator-core, in series with said device, said winding when energized tending to produce a flux in said stator-core effective to turn said armature in one direction; another winding for said stator-core, in shunt with said device, said winding when energized tending to produce a flux in said stator-core effective to turn said armature in the opposite direction; means for energizing said winding simultaneously whereby said armature turns in a direction dependent 15 upon the predominance of one of said windings over the other; said windings being disposed on said stator-core in spaced relation so that relative changes in the energizations of said windings causes substantially contemporaneous changes, in 20 said predominance, substantially proportionate to said relative changes in energizations.

8. In combination: an electrical device having a movable element the position of which influences the current through said device and the potential drop around said device; means for maintaining constant the relation between the current through said device and the potential drop around said device, comprising, an electric 35 motor drivingly connected to said movable element, said motor having a single stator-core having a pair of poles and an armature coacting with said poles, a differential field winding for said poles, said winding comprising two components, one of said components being disposed preponderantly on one pole of said pair of poles and the other of said components being disposed preponderantly on the other pole of said pair of poles, one of said components being connected 40 in series with said device and the other in shunt with said device.

9. In combination: an electrical device having a movable element the position of which influences the current through said device and the potential drop around said device; means for maintaining constant the relation between the current through said device and the potential drop around said device, comprising, an electric motor drivingly connected to said movable element, said motor having a single stator-core having a pair of poles, a differential field winding for said poles, said winding comprising two components, one of said components being disposed preponderantly on one pole of said pair of poles and the other of said components being disposed preponderantly on the other pole of said pair of poles, one of said components being connected in series with said device and the other in shunt with said device, said motor having a pair of 55 windingsless interpoles alternated with the poles carrying said components, and an armature coacting with said poles and interpoles.

10. In combination: an electrical device having a movable element the position of which influences the current through said device and the potential drop around said device; means for maintaining constant the relation between the

current through said device and the potential drop around said device, comprising, an electric motor drivingly connected to said movable element, said motor having an armature and a single stator-core for coacting with said armature; a 5 winding for said stator-core, in series with said device, said winding when energized tending to produce a flux in said stator-core effective to turn said armature in one direction; another winding for said stator-core, in shunt with said device, said winding when energized tending to produce a flux in said stator-core effective to turn said armature in the opposite direction; means for energizing said winding simultaneously whereby said armature turns in a direction dependent 10 upon the predominance of one of said windings over the other; said windings being disposed on said stator-core in spaced relation so that relative changes in the energizations of said windings causes substantially contemporaneous changes, in 15 said predominance, substantially proportionate to said relative changes in energizations.

11. In combination: an alternating current electrical device having a movable element the position of which influences the current through 25 said device and the potential drop around said device; means for maintaining constant the relation between the current through said device and the potential drop around said device, comprising, an alternating current electric motor 30 drivingly connected to said movable element, said motor having an armature and a single stator-core for coacting with said armature; a winding for said stator-core, in series with said device, said winding when energized tending to produce 35 a flux in said stator-core effective to turn said armature in one direction; another winding for said stator-core, in shunt with said device, said winding when energized tending to produce a flux in said stator-core effective to turn said armature in the opposite direction; means for energizing said windings simultaneously whereby said armature turns in a direction dependent upon the predominance of one of said windings over the other; said windings being disposed on said 40 stator-core in spaced relation so that relative changes in the energizations of said windings causes changes in said predominance substantially proportionate to said relative changes in energizations. 45

12. In combination: an electrical device having a movable element the position of which influences the current through said device and the potential drop around said device; means for maintaining constant the relation between the 55 current through said device and the potential drop around said device, comprising, an electric motor drivingly connected to said movable element, said motor having a single stator-core having a pair of poles and an armature coacting with said poles, said armature being connected in shunt with said device, a differential field winding for said poles, said winding comprising two components, one of said components being disposed preponderantly on one pole of 60 said pair of poles and the other of said components being disposed preponderantly on the other pole of said pair of poles, one of said components being connected in series with said device and the other in shunt with said device. 70
